CONVEYER SYSTEM

John E. Regan, Syracuse, N. Y., assignor to The Lamson Company, Syracuse, N. Y., a corporation of Massachusetts

Application March 8, 1935, Serial No. 9,993

2 Claims. (Cl. 198—138)

This invention relates to an improvement in a conveyer system, and more particularly to a system comprising an endless chain or other conveying element, a motor or other driving means, a track on several levels, and a plurality of cars transported by said chain along the track, said cars passing at the corners from one level or direction to another and being maintained at all times in planes parallel to a normal plane, usually horizontal.

The features of this invention reside in the provision of means at the corners of the track which engage the cars to maintain them in the desired planes during their passage around the corners from one level to another; the provision of means for taking up the slack in the chain; and in other details of structure and operation as will appear from a consideration of the following description and of the drawings which form a part thereof, and in which

Fig. 1 is a view in side elevation of a system embodying this invention;

Fig. 2 is a side elevation of the driving unit of the system;

Fig. 3 is a plan view thereof;

Fig. 4 is a view in side elevation of one corner of the system;

Fig. 5 is a view partly in elevation and partly in section taken along the line 5—5 on Fig. 4;

Figs. 6 and 7 illustrate details of the track structure;

Fig. 8 is a view similar to Fig. 4 illustrating the passage of a car around a corner;

Fig. 9 is a plan view of a car adapted to use in the system;

Fig. 10 is a view in side elevation thereof;

Fig. 11 is a view in elevation of a portion of the car;

Fig. 12 is an enlarged sectional view taken along the line 12—12 on Fig. 11;

Fig. 13 is a view similar to Fig. 1 of a portion of another system embodying this invention and having vertical runs;

Fig. 14 is an enlarged side elevation of a corner of the system shown in Fig. 13; and

Fig. 15 is an end elevation of such corner.

The typical conveyer system shown in Fig. 1 comprises a pair of parallel tracks 15 and 16 supported upon a frame made up of vertical uprights 17, horizontal rods 18, and brackets 19, an endless chain 20 traveling between the tracks 15 and 16 and passing at the corners around sprockets 21, at least one of which is driven by a motor 22 through suitable mechanism which will be described in detail hereinbelow. A plurality of cars (not shown in Fig. 1) are attached to the chain at suitable distances apart and are guided by the tracks 15 and 16.

The chain is driven by the motor 22, through a stepped pulley 23, a belt 24, a stepped pulley 25,

a countershaft 26, sprocket 27, chain 28, sprocket 29, and a gear reduction unit 30. On the unit 30 is supported the yoke 32 which carries the shaft 26, on the ends of which are fixed the pulley 25 and sprocket 27. The motor 22 and unit 30 are supported upon a block or plate 33 carried upon two horizontal bars 18 of the frame. Those sprockets 21, which are not directly driven by the motor, are each supported upon a similar block or plate 34 also carried by bars 18. The motor 22 rests on a bed 35 pivotally mounted upon the block 33 and is yieldably held by a tension device 36, which engages both the motor casing and the yoke 32, so that the belt 24 is taut regardless of which steps of the pulleys are engaged.

Mounted at the center of the unit is a main shaft 37 supported by the walls thereof. One end of the shaft 37 projects beyond the unit and on it is fixed a chain driving sprocket 21.

As pointed out above, the unit 30 and its associated parts are mounted upon the plate 33. The sprockets 21 which are not positively driven and are carried by the plates 34 rotate freely upon stub shafts 74 fixed in such plates (see Figs. 4 and 5). Mounted upon each sprocket 21 are a pair of epicyclic gears 80 which mesh with a stationary gear 81 having twice as many teeth as each gear 80 (in the present instance twelve and six), so that a half rotation of the sprocket causes one and a half rotations of each gear 80. The stationary gear 81 is mounted upon a casting 82. This casting at the gear unit 30 is provided with a bearing which receives the outer end of the shaft 37. The other castings 82 are fixed to the stub shafts 74. Formed on each casting 82 is a continuation 84 of the inner tracks, in Fig. 4 the tracks 15, the outer tracks 16 in that figure being spaced the proper distances from the extension 84, so that the car travels freely with the chain around the corner. As will be pointed out below, the gears 80 act upon the cars to maintain them at all times in parallel planes.

The car 85 may be of any type desired for the transportation of material. Figs. 9 to 12 illustrate a car of the finger or paddle type, particularly adapted for the transportation of shoes. Projecting forwardly from a flanged shelf 86 are a plurality of fingers or paddles 87 spaced apart to receive the uppers of shoes or the cones of the lasts when the shoes are lasted. The paddles 87 are secured to the shelf 86 by screws 88 through apertures 89. As indicated on Fig. 9, there are provided pairs of apertures 89 for each of the outer paddles. Thus these paddles may be mounted at different distances from the center paddle so as to accommodate shoes of different sizes.

Secured by studs 90 to the back of the shelf 86 is a plate 91 to which is fixed a gear 92 spaced from the plate 91 by a washer 93. The plate 91

is substantially rectangular and the gear 92 is mounted at the center thereof. Four rolls 94 carried by the studs 90 adjacent the corners of the plate engage the tracks 15 and 16, as shown in Fig. 8, to insure proper travel of the cars. The gear 92 has a central non-circular hole which receives a boss 95 bolted to the washer 93 and plate 91. Through the center of the boss, washer and plate are openings suitably aligned to receive a sleeve 96. A pin 97 extending through the sleeve 96 connects the car to the chain 20 so that as the chain travels the cars are moved along the track.

It will be noted from the above description that the connection of each car 85 to the chain 20 is centrally located at the back of the shelf and that of each set of four rolls 94 two engage the track 15 and the other two the track 16 at all times during the travel of the cars except when going around corners. Thus only rolling contacts are provided, and the cars travel with a minimum of frictional resistance.

The cars 85 are at all times in planes parallel to a selected plane, usually horizontal. This position of the cars is maintained as the cars travel around the corners of the track by the interaction of the tracks 15 and 16 with the engaging rolls 94, and that of the gear 92 with the epicyclic gears 80. Fig. 8 shows a car in three of the positions, designated respectively 85^a, 85^b and 85^c, which it will take while traveling around a corner of 180° from an upper level to a lower level. As the car approaches the position 85^a one of the gears 80 moves into mesh with the gear 92 on the car, and remains in mesh until the car leaves the position 85^c. Since the gears 81 and 92 are fixed against rotation and have the same number of teeth, which is double that of the rotatable gear 80, it will be obvious that the gears 40 will take the various positions shown in Fig. 8. At least two of the rolls 94 are in engagement with the tracks at all times, and such engagement, together with the engagement of a gear 80 with the gear 92, maintains the car in horizontal planes throughout its travel around the corner. As a further insurance that the car in position 85^a remains horizontal, there is formed on the track 16 a flange 98 which projects inwardly over and is engaged by rollers 99 carried by the car. 50 The tracks 15 and 16 are circular in cross section and made up in sections, each section extending between a pair of the brackets 19 mounted upon uprights 17 and rods 18. One end of each section terminates in a dowel 100 and the other end of each section is provided with a centrally located pocket 101. The tracks can thus be easily assembled, the dowel of each section passing through a hole 102 in a bracket 19 and entering the pocket 101 of the section at the 60 other side of the bracket.

The plates 34 are, as shown in Figs. 4 and 5, secured to the horizontal rods 18 by the coaction of ears 103 and U-bolts 104. In order to take up any slack in the chain 20, devices are provided by which one or more of the plates 34 may be retracted on the rods 18. Clamps 105 secured to the rods 18 adjacent each movable plate, are provided with ears 106 having holes therethrough along axes parallel to the rods 18. Through the rear wall of the plate 34 are formed holes 107 in alignment with the holes in the ears 106. Passed through the holes in each ear 106 and

through the aligned hole 107 in the plate 34 are adjusting screws 108 which engage nuts 109. By loosening the U-bolts 104 and turning the screws 108 or nuts 109, the plate 34 is retracted until the slack in the chain 20 is taken up. The 5 ears 110 on the plate receive posts 111 which connect the plate to the track 16, entering the ears 112 formed thereon. The plate when retracted thus carries with it, by reason of the stub shaft 14, the casting 82 and the continuation 84 of the 10 track 15, and also, by reason of the posts 111, the tracks 16. This movement of the continuation and tracks causes the end sections thereof to separate from the brackets 19, and the gaps so formed are measured. The chain is then opened, 15 the plate retracted until the dowels 100 leave the bracket 19 and washers 113 of the width of the gaps above-mentioned are slipped over the dowels whereupon the plate is advanced and fixed in position. 20

Fig. 13 illustrates a portion of a conveyer system having both vertical runs and horizontal runs connected by corners of 90°. As shown in Figs. 14 and 15, the chain carrying sprockets 221 mounted on the plates 234 are provided with epicyclic gears 280 which mesh with a stationary gear 281 and with the gears 92 fixed to the back of the cars 85 (not here shown). In place of the corner tracks 16 and extension 84 the plates 234 each carry tracks 300 and 301, the former connecting the tracks 216 and the latter connecting the tracks 215, being joined thereto in any suitable manner as by the use of dowels and pockets. The tracks 300 and 301 are supported upon the plate 234, the track 300 by the post 311 which 30 engages the ear 312, and the track 301 by the casting 282 which is fixed to a stub shaft 274. 35

It will be noted that the tracks of the horizontal run are nearer together than the tracks of the vertical run. This is of course due to the 40 fact that the shelf of the car is rectangular and that the distances taken vertically between the rolls are less than the distances taken horizontally. Furthermore, the cars are centrally suspended and the chain 20 travels midway between 45 the tracks.

I claim:

1. In a conveyer system wherein cars, impelled by an endless chain to which the cars are secured in spaced relation, travel on parallel tracks mounted in a vertical plane, each of said cars including a shelf having a vertical flange, a substantially rectangular plate fixed to said flange, rolls mounted between said plate and said flange and adjacent the corners of said plate for engagement with both said tracks, and a pin at the center of said plate connected to said chain. 50

2. In a conveyer system wherein cars, impelled by an endless chain to which the cars are secured in spaced relation, travel on parallel tracks 60 mounted in a vertical plane, each of said cars including a shelf having a vertical flange, a substantially rectangular plate fixed to said flange, a stationary gear at the center of said plate and having a central hole therein, a pin fixed at one 65 end to said plate extending through the hole in the gear and connected at the other end to said chain, and rolls mounted between said plate and said flange and adjacent the corners of said plate for engagement with both said tracks. 70
